(57) **CLAIM**

The ornamental design for an electrical current measurement module as shown and described.

DESCRIPTION

1. Electrical current measurement module

1.1 : Perspective

1.2 : Front

1.3 : Back

1.4 : Left

1.5 : Right

1.6 : Top

1.7 : Bottom

The parts shown by means of broken lines in the reproductions are not part of the claimed design. The dash-dot-dash broken lines shown are included for the purpose of illustrating portions of the electrical current measurement module and form no part of the claimed design. The dash-dot-dash broken lines indicate the boundary of the claimed and non-claimed parts of the design. The article of the present application is an electrical current measurement module having a substrate, three busbars and three sensor parts. The purpose of this design product is electrical current measurement.
